FIG. 30 is an end elevational view of the embodiment of FIG. 28, the opposite end elevational view being a mirror image thereof.

The dot-dash lines are included for the purpose of illustrating portions of the adhesive bandage backing layer and absorbent pad that form no part of the claimed design.

The back side plan view, opposite the illustrated plan views, of the embodiments of FIGS. 1-30 is not shown because that side of the claimed areas of the adhesive backing layer is plain and unornamented, and the back side of the absorbent pad along with the back side of the portion of the adhesive backing layer to which the absorbent pad is adhered is illustrated in broken lines and thus is disclaimed.

It will be appreciated that the adhesive backing layer is plain and unornamented in the sense that there are no decorative features on the adhesive backing layer, and that the texture or other visual appearances of the material of the adhesive backing layer is not illustrated and is not considered a part of the claimed invention.
